PROCESS FOR PRODUCTION OF KETONES

Benjamin T. Brooks, Old Greenwich, Conn.,
assignor to Standard Alcohol CompanyNo Drawing. Application July 27, 1940,
Serial No. 348,024

10 Claims. (CL 260—597)

The present invention relates to the conversion of olefin hydrocarbons to ketones and more particularly, to the conversion of both normal and branched chain olefins of five or more carbon atoms to ketones.

Lower molecular weight ketones, such as acetone and methyl ethyl ketone, have heretofore been made satisfactorily in a number of ways among which is included both the oxidation and the catalytic dehydrogenation of secondary alcohols. Higher secondary alcohols of five or more carbon atoms are, however, difficult to manufacture by the method of treating the olefins with sulfuric acid followed by hydrolysis and distillation since the action of sulfuric acid on these higher olefins causes excessive polymerization, yielding high boiling polymer oils, and in the case of branched chain olefins, substantially all of the olefins of five or more carbon atoms are converted to polymers by the action of sulfuric acid and not into alcohols. Even when the branched chain olefins are converted in small yields to tertiary alcohols, the latter cannot be oxidized or dehydrogenated to ketones.

The principal object of the present invention is to convert olefins which are readily polymerized by sulfuric acid into ketones. Another object of this invention is to treat hydrocarbon mixtures containing both normal and branched chain olefins of five or more carbon atoms to produce ketones of the branched chain hydrocarbons and at the same time to convert the normal chain olefins into either ketones or other useful products such as glycols.

The olefin raw materials employed in manufacturing ketones, according to the present invention, are olefins of five or more carbon atoms from any convenient or economically feasible source, as, for example, olefins made by the decomposition of chlorinated hydrocarbons, the decomposition of alcohols, the catalytic dehydrogenation of pentanes, hexanes, or similar hydrocarbons, fractions of cracked gasoline made by thermal cracking of petroleum oils. Gasoline made by cracking in the presence of catalytic material at relatively low pressures, and gasoline made by so-called vapor phase cracking processes cracking rapidly at high temperatures and relatively low pressures, contain large proportions of olefins and are particularly advantageous as raw material for the practice of the present invention and may be, if desired, first distilled into fractions of narrow boiling point range before

beginning the chemical operations of the present process.

5 The presence of saturated hydrocarbons in the raw material does not interfere with the chemical operations of this process and they may be subsequently separated as will be hereinafter more fully described.

According to the process of the present invention, an olefinic hydrocarbon or a hydrocarbon mixture containing one or more olefins is treated with cold dilute aqueous hypochlorous acid solution, preferably according to the process described in copending application Serial No. 306,805 filed November 30, 1939 to form chlorohydrins. The chlorohydrin or mixture of chlorohydrins thus formed is treated with solid or concentrated caustic alkali, hydrated lime or milk of lime to yield epoxides. The conversion of chlorohydrins to epoxides is preferably carried out at a temperature which will cause the epoxides to distill out as rapidly as formed.

10 The olefin epoxide or mixture of hydrocarbons containing epoxide is then treated with cold dilute aqueous mineral acid, maintaining the temperature preferably below 45° C. Sulfuric acid of from 0.1 to 1.0% concentration is the preferred acid although other mineral acids, such as nitric, may be used, and 0.5% is the preferred concentration. The dilute mineral acid causes the epoxide to be hydrated to glycol. The lower molecular weight glycols are freely water-soluble and inert hydrocarbons which may have been present in the original hydrocarbon mixture are preferably removed as an upper insoluble layer by decantation at this stage of the process. The solubility of the higher molecular weight glycols in water decreases with increasing molecular weight and in the case of hydrocarbon mixtures containing 8 or more carbon atoms to the molecule, the inert saturated hydrocarbons, if present, are more advantageously removed from the glycols by distillation with steam.

15 Glycols of five or more carbon atoms derived from branched chain olefins and containing a tertiary hydroxyl group are rapidly converted to ketones by heating with aqueous dilute mineral acids such as sulfuric or phosphoric acids of about 5 to 15% concentration by weight, but under these conditions the normal glycols remain substantially unchanged. The temperature should be maintained at or slightly above the boiling point of the ketone produced. When the original hydrocarbon mixture yields both normal glycols containing only primary and sec-

ondary hydroxyl groups and branched chain glycols containing tertiary hydroxyl groups, slow distillation from dilute acid solutions of 5 to 15% concentration yields first the ketones derived from the branched chain olefins in a substantially pure state, and on continued distillation with increasing acid concentration causes more and more of the ketones of normal olefins to be formed. This is continued until the concentration of the acid reaches about 40%. Concentrations of sulfuric or phosphoric acid greater than 40% cause coking or tar formation when making ketones of normal olefins and therefore the acid concentration is preferably maintained at about 35% by replacing the water lost through distillation. Ketones up to about 12 carbon atoms distill readily with steam under these conditions, the boiling temperature of 35% sulfuric acid being about 108-110° C. While dilute mineral acids such as nitric or hydrochloric acid cause the catalytic hydration of oxides to glycols, they are not suitable at the necessary concentrations for the conversion of glycols to ketones because of the formation of undesirable chlorination or nitration products.

The principles of the present invention are illustrated by the following examples:

Example 1

Trimethyl ethylene,

was converted to the chlorohydrins by treating a cold dilute aqueous solution of calcium hypochlorite with carbon dioxide, agitating the aqueous solution of hypochlorous acid thus formed with the pentene. The chlorohydrin was converted to the epoxide, boiling point 73°-74° C., by passing it into a vessel filled with solid caustic soda, distilling the epoxide substantially as fast as formed. 300 parts of the epoxide were added slowly with agitation and cooled to 1500 parts of water containing 15 parts of sulfuric acid, maintaining the temperature below about 45° C. 50 parts of sulfuric acid were then added and the reaction mixture was slowly distilled, the ketone distilling readily with steam. The ketone was condensed and separated from the water yielding 182 parts of methyl isopropyl ketone boiling at 92.5-93° C. and 50 parts of a higher boiling ketone, boiling mainly at 162° C. The latter ketone is a condensation product of methyl isopropyl ketone and constitutes a valuable by-product of the reaction.

Example 2

300 parts of normal pentene-2 oxide, derived through the chlorohydrin of pentene-2 was added to 1500 parts of water containing 18 parts of sulfuric acid while agitating and cooling the solution, maintaining the temperature below 15° C. The solution was concentrated by distillation to 600 parts, then 70 parts of sulfuric acid were added and the distillation resumed. 190 parts of normal amyl ketone boiling at 98°-102° C. were thus obtained the product being a mixture of methyl propyl and diethyl ketones.

Example 3

500 parts of cracked refinery C₅ cut was treated with a cold dilute aqueous solution of calcium hypochlorite in the presence of carbon dioxide. The resulting mixture was then passed into a

vessel containing solid caustic soda and maintained at a temperature and pressure sufficient to volatilize the unreacted hydrocarbons and the epoxides as rapidly as the epoxides are formed. The mixture of hydrocarbon and epoxides were then treated with a cold 1% solution of sulfuric acid which was constantly stirred and maintained at a temperature below 45° C. during the adding of the mixture. The mixture was then permitted to stand whereupon two layers formed, an upper layer consisting of unreacted hydrocarbons which were removed by decantation and a lower layer consisting of a mixture of glycols dissolved in the dilute acid. Sufficient sulfuric acid was then added to bring the acid strength up to 5% and the mixture was then slowly steam distilled, maintaining the acid concentration below 40% until all the glycols had been converted to ketones and driven off. 133 parts of a mixture of ketones was obtained.

The preceding disclosure and examples are given for the purpose of illustration only and are not to be considered as in any way limiting the invention.

I claim:

1. The process of converting olefins of more than four carbon atoms to the molecule to ketones which comprises treating the olefins with cold dilute aqueous hypochlorous acid, converting the resulting chlorohydrins to epoxides by means of concentrated alkaline reacting material, treating the epoxides with a dilute aqueous mineral acid to hydrolyze the epoxides to glycols, heating the glycol with a mineral acid of from 5 to 40% concentration selected from the group consisting of phosphoric and sulfuric acid and distilling off the ketone.

2. The process of treating a mixture of saturated and unsaturated hydrocarbons of more than four carbon atoms to the molecule which comprises treating the hydrocarbon mixture with cold dilute aqueous hypochlorous acid, converting the resulting chlorohydrins to epoxides by means of concentrated alkaline reacting material, treating the epoxides and saturated hydrocarbons with dilute aqueous mineral acid, separating the resulting aqueous glycol solution from saturated hydrocarbons and heating the glycol with a mineral acid of from 5 to 40% concentration selected from the group consisting of phosphoric and sulfuric acid and distilling off the ketone.

3. The process of converting olefins of more than four carbon atoms to the molecule to ketones which comprises treating the olefins with cold dilute aqueous hypochlorite in the presence of carbon dioxide, converting the resulting chlorohydrins to epoxides by means of strong caustic, treating the epoxides with a mineral acid of from 0.1 to 1% concentration to hydrolyze the epoxides to glycol, heating the glycol with an acid of from 5 to 40% concentration selected from the group consisting of phosphoric and sulfuric acid and distilling off the ketone.

4. The process of converting olefins of more than four carbon atoms to the molecule to ketones which comprises treating the olefins with cold dilute aqueous hypochlorite in the presence of carbon dioxide, converting the resulting chlorohydrins to epoxides by means of solid caustic, treating the epoxides with a mineral acid of from 0.1 to 1% concentration to hydrolyze the epoxides to glycol, heating the glycol with sulfuric acid of from 5 to 40% concentration and distilling off the ketone.

5. The process of converting olefins of more than four carbon atoms to the molecule to ketones which comprises treating the olefins with cold dilute aqueous hypochlorite in the presence of carbon dioxide, converting the resulting chlorohydrins to epoxides by means of solid caustic soda, treating the epoxides with a mineral acid of from 0.1 to 1% concentration to hydrolyze the epoxides to glycol, heating the glycol with sulfuric acid of from 5 to 40% concentration and distilling off the ketone.

6. The process of converting olefins of more than four carbon atoms to the molecule to ketones which comprises treating the olefins with cold dilute aqueous calcium hypochlorite solution in the presence of carbon dioxide, converting the resulting chlorohydrins to epoxides by means of solid caustic soda, treating the epoxides with sulfuric acid of from 0.1 to 1% concentration to hydrolyze the epoxides to glycol, heating the glycol with sulfuric acid of from 5 to 40% concentration and distilling off the ketone.

7. The process of converting olefins of more than four carbon atoms to the molecule to ketones which comprises treating the olefins with cold dilute aqueous calcium hypochlorite solution in the presence of carbon dioxide, converting the resulting chlorohydrins to epoxides by means of solid caustic soda, treating the epoxides with sulfuric acid of 0.5% concentration to hydrolyze the epoxides to glycol, heating the glycol with sulfuric acid of from 5 to 40% concentration and distilling off the ketone.

8. The process of converting trimethyl ethylene to ketone which comprises treating the trimethyl ethylene with cold dilute aqueous calcium hypochlorite solution in the presence of

carbon dioxide, converting the resulting chlorohydrins to epoxide by means of solid caustic soda, treating the epoxide with a mineral acid of from 0.1 to 1% concentration to hydrolyze the epoxide to glycol, heating the glycol with an acid of from 5 to 15% concentration selected from the group consisting of phosphoric and sulfuric acid and distilling off the ketone.

9. The process of converting normal pentene to ketone which comprises treating the normal pentene with cold dilute aqueous calcium hypochlorite solution in the presence of carbon dioxide, converting the resulting chlorohydrins to epoxide by means of solid caustic soda, treating the epoxide with a mineral acid of from 0.1 to 1% concentration to hydrolyze the epoxide to glycol, heating the glycol with an acid of from 20 to 40% concentration selected from the group consisting of phosphoric and sulfuric acid and distilling off the ketone.

10. The process of converting olefins of more than four carbon atoms to the molecule to ketones which comprises treating the olefins with cold dilute aqueous hypochlorite in the presence of carbon dioxide, converting the resulting chlorohydrins to epoxides by means of strong caustic, treating the epoxides with a mineral acid of from 0.1 to 1% concentration to hydrolyze the epoxides to glycol, heating the glycol with an acid of from 5 to 15% concentration selected from the group consisting of phosphoric and sulfuric acid, distilling off ketone, then heating the remaining glycol with an acid of from 20 to 40% concentration selected from the group consisting of phosphoric and sulfuric acid and distilling off the ketone.
